UNITED STATES PATENT OFFICE.

CLEMENS B. WILLENBORG, OF DYERSVILLE, IOWA.

LITTER-CARRIER.

1,022,763.

Specification of Letters Patent.

Patented Apr. 9, 1912.

Application filed August 28, 1909. Serial No. 515,106.

To all whom it may concern:

Be it known that I, CLEMENS B. WILLENBORG, a citizen of the United States, residing at Dyersville, in the county of Dubuque 5 and State of Iowa, have invented a new and useful Litter-Carrier, of which the following is a specification.

This invention relates to overhead carriers for conveying litter or any other 10 desired material from place to place by gravity.

One of the objects of the invention is to provide a novel form of bucket having improved means for locking it in a prede- 15 termined relation to its supporting frame.

Another object is to provide simple means whereby the bucket can be unlocked at any desired point, the unlocking being automatic and resulting in the inversion of the bucket 20 so as to cause the contents thereof to be dumped.

A further object is to provide improved means whereby the supporting wheels of the carrier will remain in contact with the cable 25 or track, even though the said carrier be tilted with respect to the cable as, for example, when the carrier is given an initial push to start it upon its journey.

With these and other objects in view, the 30 invention consists in certain novel features of construction and the combinations of parts hereinafter more fully described and pointed out in the claim.

In the accompanying drawings the pre- 35 ferred form of the invention has been shown.

In said drawings:—Figure 1 is a side elevation of the carrier and a portion of its supporting cable, a part of the receptacle 40 and its lock being broken away. Fig. 2 is an end elevation thereof. Fig. 3 is an enlarged section on line A—B, Fig. 1.

Referring to the figures by characters of reference, 1 designates a top bar having hangers 2 extending downward from the 45 ends thereof. These hangers and bar form a main frame. Each of the hangers is pivotally engaged by a trunnion 3 extending from one end of a trough-like receptacle 4 which is open at the top. One of the trunnions 50 extends through the center of a disk 5 secured in any suitable manner to one end of the receptacle, said trunnion being arranged concentric with the disk and the disk being provided with an annular flange 6 having a 55 notch 7 therein. This notch is designed to receive a locking stud 8 extending laterally

from the lower end of a rod 9 which is slidably mounted in the top bar 1 and also within a guide sleeve 10 which is secured to one of the hangers 2. A forked head 11 is secured to the upper end of rod 9 and carries a roller 12 which is located directly below and close to the cable 13 constituting the support of the carrier. A coiled spring 14 is mounted on the rod 9 between bar 1 and head 11 and exerts a constant upward pressure upon the head so as to hold the stud 8 normally seated within notch 7.

Hangers 15 are secured upon the top bar 1 adjacent the ends thereof and each hanger 70 is provided at its upper end with a hooked portion 16 carrying a grooved wheel 17 designed to bear upon the cable 13. Longitudinal slots 18 are formed in the hooked portion of the front hanger 15 and these slots 75 receive the trunnions 19 of the front wheel 17. A retaining block 20 is secured to the front hanger below the cable 13 and at a distance therefrom equal to the length of 80 the slots 18.

It is to be understood that the notch 7 is so located that when the stud 8 is seated therein, the receptacle 4 is held against movement relative to the hangers 2 and slightly tilted off center, as shown in Fig. 2. 85 When the carrier is given a push to start it, the front end thereof on which the locking mechanism is mounted will tend to swing upward relative to the supporting cable 13, but, in view of the fact that slots 18 are 90 provided, the front wheel 17 will remain upon the cable. Block 20 limits this upward tilting movement by coming into contact with the cable before the wheel 17 can leave it. A cam-like projection 21 may be secured 95 to the cable at the point where it is desired to dump the contents of the receptacle and when the carrier approaches this point, the roller 12 will ride against the projection and be forced downward thereby, thus moving 100 the locking stud 8 downward out of the notch 7. Inasmuch as the receptacle is normally held off center, it will be apparent that as soon as it is unlocked, the receptacle 105 will swing downward to an inverted position so as to permit its contents to drop therefrom.

It is to be understood, of course, that various changes may be made in the construction and arrangement of the parts without departing from the spirit or sacrificing the advantages of the invention.

What is claimed is:—

A carrier including a cross bar, hangers depending therefrom, a receptacle having trunnions journaled within the hangers, a 5 disk secured to one end of the receptacle and concentric with one of the trunnions, said disk having an annular flange provided with a notch, a rod slidably mounted in the cross bar and between, and in contact with, 10 the flange on the disk and the adjacent hanger, a stud upon the rod normally surrounded by the flange, a spring engaging the rod and bearing downwardly on the

cross bar for shifting the rod upwardly to move the stud into the notch when said notch 15 is brought into register therewith, and means for holding the rod against lateral movement relative to the hanger on which it is mounted.

In testimony that I claim the foregoing as 20 my own, I have hereto affixed my signature in the presence of two witnesses.

CLEMENS B. WILLENBORG.
